GEORGE F. LAURENCE, OF WATERLOO, NEW YORK.

FRITTER-FORMING MACHINE.

1,288,622.

Specification of Letters Patent. Patented Dec. 24, 1918.

Application filed August 26, 1918. Serial No. 251,414.

To all whom it may concern:

Be it known that I, GEORGE F. LAURENCE, a citizen of the United States, residing at Waterloo, in the county of Seneca and State 5 of New York, have invented a certain new and useful Improvement in Fritter-Forming Machines, of which the following is a specification.

This invention relates to improvements in 10 the construction and operation of machines for forming fritters or cakes from plastic substances such as a mixture of molasses and pop corn or the like.

An object of the invention is to provide a 15 fritter forming machine which is simple and compact in construction and efficient in operation. Another object is to provide a device which will automatically form and deliver the completed fritters as rapidly as the 20 material is fed to the machine without appreciable jarring or noise. A further object is to provide a highly sanitary machine in which all the elements are readily accessible for cleaning, inspection and repairs, 25 which is operable with minimum expenditure of power and in which danger of injury to the operator is minimized. Still another object is to provide a machine which is power driven and requires no skilled labor 30 for its efficient manipulation. A further object is to provide various improvements in details of construction of this class of machinery, which will reduce to a minimum the cost of construction and installation and 35 which will facilitate the operation thereof.

While the specific embodiment of the invention disclosed herein, is especially applicable to the formation of fritters or cakes from a mixture of molasses and pop corn, 40 it is not intended to limit the scope of the invention by such illustrative disclosure, as it will be apparent that the principles involved and the structure claimed may be applied to other machines for forming fritters or cakes from various other substances. The term "fritter" as employed throughout 45 this specification is intended to apply to any body regardless of shape, molded to a pre-determined form.

50 A clear conception of an embodiment of the invention may be had by referring to the drawing accompanying and forming a part of this specification, in which like reference characters designate the same or similar parts in the various views.

Figure 1 is a vertical longitudinal section

through a fritter forming machine, the cross-section being taken directly in front of the measuring and forming pockets and several of these pockets being shown in section. 60

Fig. 2 is a top elevation of the fritter forming machine illustrated in Fig. 1.

The fritter forming machine comprises in general a main supporting frame 17, an endless series of measuring and forming pockets 65 4, a supply bin or tank 2, a horizontal mixing table 3, a pressing device 5, a discharging device 18, a fritter delivering device or conveyer 20, and a source of driving power or motor 13. 70

The main frame may be constructed of metal bars or strips and is preferably of sufficient height to permit convenient operation of the machine when resting upon the floor. The individual measuring and 75 forming pockets 4 are of prismatic formation and have tapered openings therethrough which serve as forms for molding the fritters. The successive pockets 4 are connected by means of pivoted links 19 to form 80 an endless series comprising upper and lower horizontal stretches of end abutting pockets and curved connecting end portions. The end pockets 4 of the series engage flat faces of rotatable idler sprockets 24, 25 secured to 85 horizontal cross-shafts 15, 16 respectively, which are rotatably supported in suitable bearings mounted upon the main frame 17. The upper stretch of pockets 4 is slidably supported upon a horizontal plate 29 which 90 serves to close the smaller ends of the tapered pocket through openings. The pockets 4 of the lower stretch are inverted relative to those in the upper stretch, and are open at both ends. 95

The supply bin or tank 2 is supported upon the main frame 17 adjacent to the rear sprocket 25, and is provided with a material delivery opening controllable by means of a sliding gate or door 28. The mixing plate 100 or table 3 has a horizontal upper surface which is substantially flush with the tops of the pockets 4 in the upper stretch of the series. The mixing table 3 is provided with an inclined plate 34 at one end thereof, 105 which terminates at the opening of the tank 2.

The pressing device 5 comprises a circular revoluble series of equally spaced plungers which fit and are adapted to enter the 110 tapered through openings of the pockets, and which are spaced apart circumferen-

tially distances equal to the distances between the openings of successive pockets 4 of the horizontal upper stretch. The pressing rotor or device 5 is secured to a horizontal cross-shaft 10 which is rotatably mounted in suitable bearings secured to the main frame 17. Rigidly secured to the cross-shaft 10 is a worm wheel 6 which meshes with a worm 8 secured to the upper extremity of the vertical drive shaft 9. The drive shaft 9 is supported in bearings associated with the main frame 17 and has a sheave or grooved pulley 7 secured to the lower portion thereof. The pulley 7 is drivingly connected by means of a cable or belt 11, with a sheave or grooved pulley 12 secured to the horizontal shaft of a driving element such as the electric motor 13. The motor 13 is preferably mounted upon the main frame 17 and is controllable by means of an ordinary snap switch also preferably associated with the main frame 17.

Directly above the lower horizontal stretch of the endless series of pockets 4 is located a fritter discharging device 18 which comprises a circular revoluble series of plungers adapted to enter the smaller ends of the tapered through openings of the successive pockets 4. These plungers which are four in number are spaced apart circumferentially distances equal to the distance between the openings of successive pockets 4. The discharging device 18 is secured to a horizontal cross-shaft 31 rotatably mounted in suitable bearings secured to the main frame 17. The discharging device 18 is rotatable by the movement of the pockets 4 which engage the successive plungers of the device. Located directly below the discharging device 18 and secured to the main frame 17 below the lower horizontal stretch of pockets 4, is a stationary fritter guide 21 having a guiding surface which is directed toward the surface of the conveyer 20. The conveyer 20 comprises an endless belt or band coacting with two or more guide pulleys not shown, and with a driving pulley 27 secured to the horizontal cross-shaft 26. The cross-shaft 26 is mounted in suitable bearings secured to the main frame 17 and has a sheave or grooved pulley 33 secured thereto, which is drivingly connected with a similar sheave or grooved pulley 32 secured to the front cross-shaft 15, by means of a driving cable or belt 23.

The machine is preferably provided with suitable guard plates surrounding the worm gearing and has a guard plate 30 in advance of the pressing device 5, in order to protect the operator. The retainer guide 22 which is stationarily suspended from the main frame 17, prevents the fritters from dropping from the pockets 4 as they are inverted, until the discharging device 18 has been reached. A water-box 14 secured to the

front of the machine facilitates moistening of the hands of the operator. The entire frame structure is preferably nickel plated or enameled in order to facilitate keeping the machine in sanitary condition as well as to give the device which is ordinarily installed in a public place, a highly attractive appearance.

The machine may be readily placed in operation by manipulation of the motor controlling switch to start the motor 13. The rotation of the motor shaft is transmitted through the sheave 12, belt 11 and sheave 7 to the vertical drive shaft 9 and worm 8. As the worm 8 revolves, it rotates the worm wheel 6, horizontal cross-shaft 10 and the pressing device 5 in a clockwise direction as indicated by the arrow. The revolving plungers of the pressing device 5 approach the successive pockets 4 and enter the tapered openings of these pockets. As the leading edges of the plungers of the pressing device 5 engage the walls of the pocket openings, they advance the series of pockets 4 and cause the front and rear sprockets 24, 25 to rotate. The pressing device 5 thus serves as a cog-wheel for driving the endless series of pockets 4, as well as performing the function of pressing the contents of these pockets.

The rotary motion of the front sprocket 24 is transmitted through the horizontal cross-shaft 15 to the grooved pulley 32 from which the motion is transmitted through the belt 23, pulley 33, cross-shaft 26 and driving pulley 27 to the belt conveyer 20, causing the upper flight of the conveyer to move toward the left as viewed in the drawing. The advancing pockets 4 are inverted as they pass around the front sprocket 24 after which they approach and successively engage the plungers of the discharging device 18. The plungers of this device 18 enter the successive pockets 4 and engage the side walls thereof, the discharging device being thus continuously rotated by the pockets.

The mixture of pop corn and molasses from which the fritters are commonly formed, is admitted to the mixing and forming table 3 from the tank 2 over the inclined plate 34. From the mixing table 3 the operator pushes or slides batches of the mixture into the successive pockets 4 as they rest upon and slide over the plate 29. The pockets 4 are thus filled to substantially their upper extremities with mixture and are advanced in this condition past the guard plate 30 and below the plungers of the pressing device 5. The pressing plungers engage the material in the pockets 4 and compress the same against the plate 29 and the pocket walls, thus forming the fritters of uniform size and shape. The compressed fritters are then automatically advanced to the region of the discharging device 18. The plungers of this device 18 enter the successively ap-

proaching inverted filled pockets 4 and force the finished fritters therefrom. The discharged fritters gradually drop upon and slide along the guide 21 from which they 5 are delivered upon the conveyer 20 and discharged from the machine. The finished cakes or fritters are then arranged in stacks of five or more and are packed in cartons or in wax-paper when they are ready for sale.

10 The speed of operation of the machine is such that the manual filling of the pockets 4 is readily effected. The worm gearing and belt drives eliminate noises which would be undesirable in places where such machines 15 are ordinarily installed. The revolving pressing device 5 provides an effective means for simultaneously compressing the fritters and imparting motion to the remainder of the moving mechanism. The transmission 20 of this motion is also exceedingly noiseless since the pressing plungers gradually approach, engage and leave the pockets 4 without creating shocks or jarring the pockets. The transmission of motion from the 25 pockets 4 to the discharging device 18 is likewise exceedingly silent thus producing a complete mechanism of simple construction, high efficiency and silent operation.

It should be understood that it is not desired to limit the invention to the exact details of construction herein shown and described for various modifications within the 30 scope of the appended claims may occur to persons skilled in the art.

35 It is claimed and desired to secure by Letters Patent:—

1. In a fritter forming machine, a series of pockets having frusto-conical downwardly tapered openings, a series of plungers coöperable directly with said pocket openings to move said pockets and to compress material, means for inverting said pockets, and a series of ejectors coöperable with said pocket openings to expel material from said pockets while inverted, said ejectors being movable by said pockets.

2. In a fritter forming machine, a series of pockets having frusto-conical down-

wardly tapered openings, a series of plungers coöperable directly with the leading 50 ends of said pocket openings to move said pockets and to compress material, means for inverting said pockets, and a series of ejectors movable through coöperation directly with the trailing ends of said pocket openings to expel material from said pockets while inverted.

3. In a fritter forming machine, a source of power, a series of plungers, worm gearing drivingly connecting said source and said 60 plungers to move the latter, and a series of pockets having frusto-conical downwardly tapering openings, said plungers being coöperable directly with said pocket openings to move said pockets and to compress ma- 65 terial therein.

4. In a fritter forming machine, a source of power, a series of plungers, worm gearing drivingly connecting said source and said 70 plungers to move the latter, a series of pockets having frusto-conical downwardly tapering openings, said plungers being coöperable directly with the leading ends of said pocket openings to move said pockets and to compress material therein, means for inverting said pockets, and a series of ejectors 75 movable through coöperation directly with the trailing ends of said pocket openings to expel material from said pockets while inverted.

5. In a fritter forming machine, a series of pockets having frusto-conical downwardly tapered openings, a series of plungers coöperable directly with said pocket openings to move said pockets and to compress material, means for inverting said pockets, a series of ejectors coöperable with 85 said pocket openings to expel material from said pockets while inverted, and a conveyer movable by said inverting means, said 90 ejector being movable by said pockets at a slower speed than said conveyer.

In testimony whereof, the signature of the inventor is affixed hereto.

GEORGE F. LAURENCE.
